UNITED STATES PATENT OFFICE

2,469,853

MULTISECTION ENVELOPE AND BLANK FOR
FORMING THE SAMEThomas A. Terry, New York, N. Y., assignor to
C. & M. Envelope Company, New York, N. Y.,
a corporation of New York

Application April 10, 1945, Serial No. 587,534

1 Claim. (Cl. 229—72)

1

This invention relates to envelope constructions and more especially to envelopes having a plurality of discrete sections or pockets on the interior thereof.

A principal object is to provide a novel blank for forming a multi-section envelope.

Another object relates to an envelope having a plurality of separate partitioned sections on the interior and a common sealing flap, all of which are formed from a single foldable blank. This arrangement avoids the necessity of employing partition members which are cut separately from the envelope blank per se, and also avoids the necessity of a separate assembling and fastening operation between the individual partitions and the body of the envelope.

A further object is to provide an improved blank for a multi-section envelope which can be manufactured on standard envelope making machines.

A feature of the invention relates to an envelope having a plurality of discrete pockets or compartments on the interior thereof.

Another feature relates to an improved mailing envelope and the like having three discrete pockets or compartments which are formed from a single blank.

A further feature relates to a mailing envelope and the like having a plurality of individual pockets or compartments on the interior, the envelope having a main sealing flap for all the pockets and an auxiliary sealing flap for certain of the pockets only.

A still further feature relates to the novel organization and arrangement of parts which cooperate to provide a multi-section envelope which can be inexpensively manufactured on existing envelope making machines.

Other features and advantages not specifically enumerated will be apparent after a consideration of the following detailed descriptions and the appended claim.

In the drawing which shows certain preferred embodiments,

Fig. 1 shows an improved envelope blank and folding method according to the invention.

Fig. 2 is a view of the blank of Fig. 1, showing one of the folding steps.

Fig. 3 is a view (partly broken away) of the finished envelope made from the blank of Fig. 1.

Fig. 4 is a sectional view of Fig. 1, taken along the line 4—4 thereof.

Fig. 5 represents a modification of the blank of Fig. 1.

2

Fig. 6 represents the finished envelope made from the blank of Fig. 5.

Fig. 7 represents a second modification of Fig. 1.

Fig. 8 represents the envelope (partly broken away) and made from the blank of Fig. 7.

Fig. 9 is a sectional view of Fig. 8, taken along the line 9—9 thereof.

Fig. 10 represents a third modification of Fig. 1.

Fig. 11 is a view of the finished envelope (partly broken away) and made from the blank of Fig. 10.

Fig. 12 is a sectional view of Fig. 11, taken along the line 12—12 thereof.

Referring to Figs. 1 to 4, there is shown a blank

1 of paper, cardboard or other suitable stock conventionally employed in the manufacture of envelopes. The blank is cut from the desired stock to the shape shown in full lines in Fig. 1. It is constituted of a main body section 2; lateral flap sections 3, 4; a lower flap section 5; a top flap section 6, and an intervening double folded edge section 7. The section 7 is preferably provided with reentrant edge portions 8 and 9 as shown.

In accordance with the invention, the section 2 constitutes the front or face of the finished envelope; the sections 3 and 4 when folded over and united, form the back or rear face of the envelope; the section 5 forms a dividing partition extending internally throughout the length of the envelope. The section 6 forms the usual overall sealing flap on the top of the envelope, while the section 7 forms a double folded section for strengthening and closing-off the bottom edge of the envelope.

The dotted lines A, B, C, D1 and D2 represent 35 the fold lines to indicate that the folds are made in the order A, B, C, D. The several folds are all made in the same direction, that is, upwardly out of the plane of the paper. This constitutes a very important feature of the invention, in that it enables the blank to be folded on conventional folding machines, since all the folds are made in the same general direction. The upper edge of section 6 is provided with a surface strip 10 of glue or other sealing composition ordinarily employed

40 in sealing envelopes. Likewise, the edge of section 4 is provided with a strip 11 of sealing glue or composition.

Fig. 2 shows the first folding step wherein the section 5 is folded upwardly along the fold line 45 A. Preferably the edges 12 and 13 of section 5 are very slightly cut on a taper so that when the section 5 is folded to the position shown in Fig. 2, it slightly clears the fold lines B and C. The section 3 is then folded over to the position shown 50 in Fig. 3, and then the section 4 is folded over and

the strip 11 is glued to the corresponding surface of the folded-over section 3. The final folding step comprises the refolding-over of the section 7 along the superposed fold lines D1, D2. The face of the section 7 is then glued to the outer surface of the folded-over sections 3 and 4 as indicated in Fig. 3. As shown in Fig. 4, the finished envelope comprises two completely separate pockets 14, 15, which are separated by the section 5 of the blank which forms a continuous partition therebetween. If desired, the original blank may be lightly scored along the fold lines to facilitate the folding operation.

Referring to Figs. 5 and 6, there is shown a modification of Figs. 1 to 4. The blank of Fig. 5 is identical with that of Fig. 1, except that the section 5 is provided with an additional lip or flap 16, which has a surface strip of glue 17, and which can be folded along the line E to seal the pocket 15 individually. With this arrangement, matter can be inserted in pocket 15 and sealed, and other matter can be inserted in pocket 14 and sealed by the main flap 6 which overlies the auxiliary flap 16.

Figs. 7 to 9 show a further modification, wherein the finished envelope has three separate pockets extending the full length of the envelope interiorly thereof. The blank 1 is substantially the same as the blank of Fig. 1, except that the lateral sections 3A, 4A, are cut sufficiently long so as to overlie substantially the entire length of section 2. Each of the sections 3A and 4A has an individual gluing strip 18, 19, at the ends so that when the said sections 3A and 4A are folded over as described in connection with sections 3 and 4 (Fig. 1), they can be individually glued thus forming three separate pockets 14, 20 and 21 (Fig. 9). The manner of folding and gluing the blank of Fig. 7 is otherwise the same as that described in connection with Fig. 1.

Figs. 10 to 12 show a further modification of Fig. 7, wherein either or both of the lateral sections 3A is provided at its middle portion with an additional gluing strip 22, 23, on opposite 45 faces, so that when the two sections 3A and 4A are folded over each other, they can be glued at the central region 24, thus subdividing the outer pocket into two smaller pockets 25, 26.

Thus, the finished envelope as shown in Fig. 11, comprises two pockets 14 and 15, extending substantially the entire interior length of the envelope, and two additional pockets 25 and 26, extending each approximately half the length of the envelope. The manner of folding the blank of Fig. 10 is the same as that described in connection with Figs. 1 and 7.

While certain particular embodiments have been disclosed herein, various changes may be made therein without departing from the spirit and scope of the invention.

What I claim is:

An envelope formed from a single unitary folded paper blank, said blank having a central portion to form the front of the envelope and having the same size as the finished envelope said front portion having a top wing to form the sealing flap of the envelope, and having a bottom wing of at least the same size as said front portion and arranged to be folded against said front portion to form a partition for dividing the envelope into two distinct compartments said front portion also having a pair of lateral wings each being shorter than the length of said front portion and arranged to be folded towards each other to form the back of the envelope, said bottom wing being initially folded along a line which is off-set below the lower edge of said front portion to form an overhang said overhang being refolded back on itself along the bottom edge of said front portion and sealed to said folded-over lateral wings to seal the bottom of the envelope and to provide a reinforcement therefor.

THOMAS A. TERRY.
